ATTORNEY

UNITED STATES PATENT OFFICE.

MICHAEL SZTANKOVITS, OF COLLEGE POINT, NEW YORK.

LAMP-EXTINGUISHER.

1,114,551.

Specification of Letters Patent.

Patented Oct. 20, 1914.

Application filed May 6, 1914. Serial No. 836,827.

To all whom it may concern:

Be it known that I, MICHAEL SZTANKOVITS, a subject of the King of Hungary, residing at College Point, in the county of 5 Queens and State of New York, have invented certain new and useful Improvements in Lamp-Extinguishers, of which the following is a specification, reference being had therein to the accompanying drawing.

10 This invention relates to a lamp extinguisher, and has for its object to provide a device of such class, in a manner as hereinafter set forth, for extinguishing the flame of a lamp when the latter is tilted or upset.

15 Further objects of the invention are to provide a lamp extinguisher which is comparatively simple in its construction and arrangement, automatic in its action, readily applied to a lamp burner, efficient in its use,

20 strong, durable, and inexpensive to manufacture.

With the foregoing and other objects in view, the invention consists of the novel construction, combination and arrangement of 25 parts as hereinafter more specifically described and illustrated in the accompanying drawings, wherein is shown an embodiment of the invention, but it is to be understood that changes, variations and modifications 30 can be resorted to which come within the scope of the claim hereunto appended.

In the drawings wherein like reference characters denote corresponding parts throughout the several views: Figure 1 is 35 a vertical sectional view of a lamp burner showing the adaptation therewith of an extinguishing device in accordance with this invention, Fig. 2 is an elevation of the extinguishing device, Fig. 3 is an inverted plan 40 of the burner, and Fig. 4 is a perspective view of the extinguishing device.

Referring to the drawings in detail, 5 denotes a burner, provided with a wick tube 6 and further having secured to the lower 45 end thereof a plate 7 for swivelly connecting with the burner a vertically disposed holding rod 8 having a weight 9 at its lower end. The rod 8 extends up into the burner at one side of the wick tube and is normally re-

tained in a perpendicular position in a manner to be hereinafter referred to, but is capable of shifting from its normal position when the burner is tilted or the lamp upset. The swivel connection between the rod 8 and the plate 7 is indicated at 10.

55

Pivots connected in the burner 5, at the top thereof, as at 11 and 12 is an arcuate extinguisher member 13, and which has one end formed with an arc-shaped slot 14 through which extends a stop pin 15. The 60 member 13 is furthermore provided with an apertured ear 16, having attached thereto one end of a coiled spring 17, the other end of the latter being fixed to a lug 18, carried by a plate 19, secured within the burner 5, 65 as at 20. The function of the spring 17 is to shift the member 13 to extinguish the flame.

The member 13 has secured thereto an inwardly extending angle-shaped arm 21, provided with a depending extension 22, formed with a cap 23, which forms a socket 24, for the pointed upper end 25 of the rod 18. When the pointed end 25 of the rod 8 extends into the socket 24, the action of the 75 spring 17 is arrested and the extinguisher member is in the position as shown in Fig. 1 of the drawings. If the burner or lamp should tilt or the lamp in which the burner is attached upset, the action of the weight 80 9 will shift the rod 8 from out of the socket 24, and under such conditions the spring 17 will shift the member 13 to extinguish the flame. The pivot 12 extends from the burner 5 and is provided with a finger piece 85 27 for the purpose of restoring the member 13 to inoperative position, such position being as illustrated in full lines in Fig. 1. Operative position of the member 13, is as indicated in dotted lines in Fig. 1.

90

What I claim is:—

A lamp extinguisher comprising the combination with a burner, of a counterbalanced holding rod pivotally connected to and extending up into said burner, a spring 95 controlled extinguisher member pivotally connected within said burner and provided with an angle-shaped arm having a depend-

ing portion formed with a pocket adapted for the reception of said rod for holding the member in an inoperative position against the action of its spring, said member being formed with an arc-shaped slot, and a stop pin connected to said burner and extending in said slot being adapted for limiting the movement of said member.

In testimony whereof I affix my signature in the presence of two witnesses.

MICHAEL SZTANKOVITS.
